UNITED STATES PATENT OFFICE.

NELSON A. LOCKWOOD, OF OGDEN, UTAH.

KNIFE-SETTING MACHINE.

1,405,790.

Specification of Letters Patent. Patented Feb. 7, 1922.

Application filed February 11, 1921. Serial No. 444,248.

To all whom it may concern:

Be it known that I, NELSON A. Lockwood, a citizen of the United States, residing at Ogden, in the county of Weber and State 5 of Utah, have invented certain new and useful Improvements in Knife-Setting Machines; and I do hereby declare the following to be a full, clear, and exact description of the invention, such as will enable others 10 skilled in the art to which it appertains to make and use the same.

This invention relates to knife setting machines of a character devised for mechanically adjusting the corrugated slicing knives 15 as arranged in sets, in their knife supporting blocks, preparatory to loading the revoluble drum of certain types of beet cutters primarily, although the invention may later be found to be equally susceptible for use in 20 other analogous relations.

The object of slicing the beet roots as cosette chips, the corrugated form of knives with their knife supporting blocks, and an 25 illustrative type of beet cutting drum machines, employed in such connections, have all been fully and clearly disclosed in my prior patent #1,339,210, of May 4, 1920, to which reference may be had for more detailed information, and it would serve no 30 particularly useful end to repeat them herein; but the resulting liability of abnormally cut cosettes, from the method of setting the knives as theretofore practiced, and the 35 serious disadvantages thereof, may well be restated and emphasized as follows:—

As practiced prior to the time of my former disclosure, set forth in the aforesaid patent, the operative placed the knife supporting blocks on an ordinary work bench, 40 or other convenient support, and bolted the sharpened knives in position without any attention whatsoever as to their being in proper alignment, as it would be very difficult to manually adjust them for that purpose. As these knives have corrugated 45 cutting sections, preferably triangular in cross-section, which follow each other in edgewise circumferential series, it is manifest that abnormal cosettes will result when 50 the cutting sections of one knife are out of line with those of a preceding or a following knife, being cut thicker on one side than on the other. It is extremely important, however, that the cosettes, or hollow prismatic 55 beet chips, should be of uniform ribbon-like thickness on both sides, as a great loss is

otherwise experienced in the sugar contents exuded by diffusion.

As in my former patent, therefore, the primary object of the present invention is 60 also to provide simple and effective mechanical adjusting means, functioning to positively and accurately center or spot the knives so that their cutting sections will be congruently aligned circumferentially, and 65 thus insure the evenly sliced cosettes requisite for the maximum procurement of their sugar contents, while at the same time devising such a particular form of machine, the altered structural arrangement and detailed 70 assembly of which provide improvements that are peculiarly suited to the needs of smaller sugar mills, requiring a smaller and less costly machine for use in handling only one knife block at a time, instead of the full 75 complement of knife blocks usually comprising a set of approximately eight knife blocks loaded into the drum of the average beet cutting machine.

These as well as other objects and advantages will be so clearly apparent, however, as incidental to the following disclosure, that it is unnecessary to further enlarge upon the same, and with these prefacing remarks reference will now be immediately 80 had to the accompanying drawings, illustrating a practical embodiment of the present improvements, in which drawings—

Figure 1 is a view in side elevation of the new machine, partly broken away and partly 85 shown in section in some few places for a clearer conception of interior construction; Figure 2 is a view in front elevation, the knife block being broken away, for convenience, to show only one of the knife sections, which are disposed in endwise pairs, and of which there are three sets in reality 90 as in Fig. 4; Figure 3 is a local plan view at the upper right hand side of Fig. 1, as indicated by the section line 3—3 across the 95 counterbalancing weight arm; Figure 4 is a longitudinal sectional view through one of the knife blocks, mounting the endwise paired sets of corrugated knives, and which also would indicate its disposition during 100 the lowermost zone of clockwise travel when in its beet cutter drum, but which forms no part of the invention proper and is only illustrative of the application thereof; and Figure 5 illustrates a grouped end view of 105 three cosettes, two of which are abnormally cut while the other one is correctly cut, with

reference to the speedy maximum procurement of their sugar contents in the diffusion process.

10 designates a base support to which the 5 standard 11 is secured, the upper end of the latter providing a horizontally disposed strap bearing 12, controlled by fastening bolts 13, and the standard 11 also providing towards its lower end a horizontal arm 14, 10 terminating in an axial stub 15 that has an axial threaded end socket 16 and a peripheral socket 17, the latter for receiving the end of a taper pin 18, which may be 15 flexibly connected to the standard, as by a chain 19, to prevent its misplacement.

The knife block support may preferably be reversibly mounted by the axial stub 15, and to this end the latter is shown as being encompassed by a snugly fitting sleeve 20 20 that may be formed integrally with the knife block support, as later referred to, and the peripheral wall of the sleeve may also be apertured, as at 23, to provide for a grease cup 24.

25 The lower periphery of the sleeve 20 is formed with a longitudinal rib projecting substantially forward as a lug extension 25 that has a threaded vertical bore to receive a set-screw element 26, the upper end of 30 which is formed as a cone 27 and the lower end having a manual controlling element, such as an operating handle 28.

The knife block support proper is of 35 bifurcated structure and may comprise a transverse base bar 29 providing the forwardly projected parallel elongated side bars 30, which are formed with suitably beveled recesses 31 along the whole length of their upper inner faces (see Fig. 2) to provide 40 supporting guideway ledges for slidably receiving the end walls of the inserted knife block, it being observed that the side bars 30 are substantially spaced apart and that the arrangement permits of the knife block 45 being inserted sideways from the outer end of its support, for sliding inwardly to proper position for the desired knife adjusting or centering.

The sleeve 20 may be integrally formed 50 with the base bar 29 as a rearwardly extended central hub therefor, and a smooth axial bore 22 is provided that is in alignment with the threaded socket 16, for the reception of a stud bolt 32, while the base 55 bar 29 may also be counterbored, as at 21, to receive the nut of said bolt, if a stud bolt, or the head thereof if in the form of a cap screw. By this arrangement, the bolt 32 is firmly screwed home in the threaded 60 socket 16, as a fixed axis pin for the hub sleeve 20 and its knife block support, the bore 22 encompassing the axis pin in pivotal relation, as will be apparent.

As will later appear, there is a good reason 65 for thus pivotally mounting the knife block

support, whereby its position may be reversibly altered, completely or partially, and it will be understood that this arrangement is an additional improvement with relation to the more important one of mechanically 70 aligning the knives themselves, the co-operating novel means for accomplishing which latter will now be entered into fully.

An upper horizontal arm 35 projects forwardly of the standard 11, in the plane of 75 the lower arm 14, and terminates over the knife block support.

The body portion of this arm is shown as tapering and as having an annular abutment shoulder 36, with a reduced cylindrical rear 80 end 37, the latter for mounting in the strap bearing 12. The forward end is also cylindrical, as at 38, and has an abutment shoulder 39 that is formed with a pair of upwardly projected spaced lugs 40, to provide a vertical guide slot for the horizontal latching arm 42 of a bell crank lever, which is pivotally secured to the arm 35, as by the spaced ears 41. The said latching arm 42 of the bell crank lever is adapted to project 90 forwardly of, and in contained relation with, its guide abutment lugs 40, while the vertical arm 43 of the lever serves as an actuating handle therefor.

45 indicates a vertically suspended, or pendulum-like, pivoted arm that is mounted to swing transversely of the machine and therefore longitudinally over, or in the arc of, the knife block support.

The upper end of this arm provides a 100 bearing sleeve 46 that encompasses the cylindrical end 38 of the horizontal arm 35, and 47 is an end retaining disk, for the bearing sleeve, apertured to receive a cap screw 48 that threads into the horizontal arm 105 end 38.

The rear edge face of the bearing sleeve 46 abuts against the shoulder 39, and provides a peripherally notched segment 49, the notches of which are adapted to receive the 110 projected end of the lever latching arm 42 for holding the swinging arm 45 in variably set angular positions.

The bearing sleeve 46 may also provide an upwardly projected lug plate 50 to which 115 may be secured a vertical bar 51 to adjustably mount a sliding counterbalancing weight 52 for the swinging arm 45.

The lower end of the latter provides a forwardly disposed offsetting bend 53, terminating in an upright and vertically apertured elongated guiding foot 54 for receiving a retractile plunger bar 55. The upper end of the latter is capped with an operating head 56, or its equivalent, and an encompassing 125 spring 57 encircles the bar between its capping head and the top of the guide foot, while the lower end of the bar may be tapered to fit a correspondingly bored shank of a knife centering member 59, suitable aper- 130

tures being provided and a taper pin 58 associated therewith to securely attach the knife centering member to the retractile bar. The vertical aperture through the guide foot 54 could be other than a cylindrical bore if desired, with the bar 55 formed accordingly, to prevent the latter from turning any, although it is believed that the matter is unessential and the formations may be cylindrical as shown.

It will be seen from Fig. 1, as viewed with Fig. 2, that the knife centering member 59 is simply in the form of an elongated rectangular shoe that has its bottom face 15 transversely serrated at 61—62, with an intermediate recess or gap 60, the serrations substantially corresponding with the external corrugated surface of the cossette cutting knives, the gap 60 functioning to straddle the abutting inner ends of a pair of knives being centered.

The foregoing description in reality covers the actual elements embodied by my improvements, but before setting forth the 25 manner of their operation it is desirable to refer to the mounting of the corrugated beet cutting knives, for the proper aligning of which the invention is especially devised.

The knife blocks (see particularly Fig. 4) 30 embody segmentally curved frame sections, adapted for insertion in a beet cutter drum, comprising side walls 65 and cross bars 66, the latter being formed with a vertical web surmounted by a forwardly projecting flat 35 transverse support 67 and a rearwardly projecting transverse support 68, having a concaved upper face with slots 69 opening downwardly therefrom to house adjustable swinging bolts 70 that are connected with cutting 40 regulating guide bars 71 having convex bottoms rotatably seated in said concave supports. The knives consist of elongated flat bases having an upwardly offset and forwardly projecting series of corrugated (in 45 this case serrated) hollow slicing members 73 terminating in forward cutting edges. The knife bases have a pair of rear edge slots 75 converging inwardly and co-operating with longitudinal slots 74, in the base supports 67, and with anchor bolts 76 for securing the knives on their supports 67. Seating means for set-screws are provided intermediate of the ends of the outer edge faces of the sides 65, and such suitable means are 50 indicated by one of a pair of threaded studs 77 having beveled recessed heads 78, although in my machine only one of these seating stud elements is actually needed to be engaged by a setting screw for that particular 55 block.

As would be indicated by the division line 72, at Fig. 1, the knives are mounted in end-wise pairs on the blocks and, as before stated, under methods prior to my inventions no attempt whatever was made to bring the cut-

ting edges of the several pairs of knives of each block, and hence those of the several blocks themselves, into congruent alignment. For instance, it may be noted that where the central pair of knives are out of line with reference to the end pairs, the beet chips will be cut heavy on one side and light on the other, as indicated by the cossette *a* at Fig. 5, whereas the rear pair of knives being in proper line with the forward pair, but immediately following the central pair out of line, the beet chips will be cut heavy on the other side, as indicated by the cossette *b*. Thus with this one bad adjustment alone there results a plurality of series, across the machine cutter, of abnormally cut chips of at least two different forms, which serious defect is proportionately made worse when the knives of other blocks in the drum cutter are also out of line, because normal cossettes *c* will only occur when the cutting edges of the knives of the series are in congruent circumferential alignment.

Operation.

As a matter of fact, a knife block may be unloaded of its dulled knives and a set of sharpened knives placed thereon, and lightly secured for final adjustment, before utilizing my machine at all; but on the other hand the whole operation may be done on the machine and will be so described.

Assuming, therefore, that the arm 45 is swung to either side and held in a horizontal position, out of the way of the operative, by the detent or latching arm 42 being dropped into one of the notches 49, or for that matter by the weight of the counter-balancing arrangement 50—51—52, then a knife block with dulled knives may readily be slid 105 into the knife block support of my machine as in Fig. 1 and 2 (although the arm 45 is there shown in centering position for the knives of a sharpened set) when the set screw 26 would be operated to cause its cone head 27 to enter the recessed head 78 of the knife block stud 77. The block is held against longitudinal play by its snugly fitting the beveled seats 31, and that particular knife block as well as all 110 others so inserted will be held set in the knife block support in identically the same position by the set screw arrangement just referred to. Regardless of their knives, therefore, the knife blocks are themselves 115 centered on the knife block support of the machine.

The taper pin 18 may now be withdrawn and the block support wholly or partially reversed to bring the nuts 76 into more convenient position for loosening up and removing the dulled knives.

Paired sets of sharpened knives are then attached to the emptied knife block, when they are initially fastened to hold them not 130

too tightly, but without any regard at all as to their true alignment. This reloading could be done when the knife block support is in a partially reversed or tilted position 5 only, if desired, but at any event, when the sharpened knives are so loosely set initially, it is necessary that the parts be made to assume the position shown in the drawings for knife centering adjustments, with the 10 knife block support firmly held in its horizontal plane by the replacement of the taper pin 18.

The tram arm 45 being a radius arm relatively to the arc of the knife block, it is 15 immaterial which pair of knives are first adjusted, but in the drawings it happens that the tram arm is centrally disposed.

Upon now operating the plunger rod 55 downwardly, it follows that the serrated 20 faces 61—62 of the shoe 59 will engage the external surfaces of the corrugated central knife sections 73, with the gap 60 spanning the inner end division space 72 of that pair of knives. This operation will obviously 25 draw the pair of knives inwardly towards each other, or reversely will slightly spread them apart as the case might be, thus bringing them to a centered or spotted position that will be common to every pair of knives 30 so operated on in that block, or any other block.

A pair of the knives being now accurately spotted and held in such adjusted position by the serrated centering shoe, the nuts 76 35 are further tightened up from underneath during that time. The tram arm, being free to oscillate back and forth, may then be swung to another position to adjust another pair of the knives. When all of the knives 40 of a block have been thus centered, the knife block support may again be wholly or partially reversed, to more conveniently screw the nuts 76 securely home, as they must finally be made very tight, preparatory to 45 the block of sharpened knives being loaded into the beet cutter drum.

As shown in the drawings, the slots 49 are diametrically opposed, to receive the detent 42, for holding the tram arm 45 latched in 50 a horizontal position in either direction, when the operative is taking out the knives and replacing them by a new set. When the arm 45 is pendent, however, it is free to oscillate freely back and forth across the 55 knife block for the purpose of aligning the knives. As a matter of fact, however, these slots 49 need not necessarily be diametrically opposed, and indeed if it were found desirable, there might be several more intermediate 60 slots which would enable the arm to be held latched in positions directly radial to each set of the successive knives, although it is not thought that this would be necessary and would necessitate the operation of 65 the detent 42 each time the setting shoe 59

was shifted from one pair of knives to another.

While I have thus made a complete disclosure of a practical embodiment of my improvements, it may later be found to be desirable or expedient to make minor alterations or substitutions in the form and structural arrangement of elements, but without departing from the scope and spirit of the invention, and it will be understood, therefore, that I do not limit myself necessarily to the exact details shown and described, excepting as they may come within the terms of the ensuing claims or as fairly interpreted in the light of the specification and understood equivalents.

What I do claim, as new and patentable, is:—

1. In knife setting machines of the character disclosed, the combination with a 85 knife block support for removably holding, in substantially horizontal disposition, a knife block that mounts endwise paired cossette slicing knives, of mechanical centering means adapted to span the abutting ends of said knives, when so disposed, and radially operable to engage and adjust said knives in 90 an endwise direction relatively to each other, substantially as described.

2. In knife setting machines of the character disclosed, the combination with a flatwise reversible knife block support for removably holding, in reversible substantially horizontal disposition, a knife block that mounts endwise paired cossette slicing knives, of mechanical centering means adapted to span the abutting ends of said knives, when so properly disposed, and radially operable to engage and adjust said knives in an endwise direction relatively to each other, substantially as described.

3. In knife setting machines of the character disclosed, the combination with a knife block support for removably holding, in substantially horizontal disposition, a knife block that mounts endwise paired cossette slicing knives, of means co-operating with complementary means of said knife block for centering said knife block on its support, and mechanical centering means adapted to span the abutting ends of said paired knives, when so supported, being radially operable thereof to engage and adjust said knives in an endwise direction relatively to each other, substantially as described.

4. In knife setting machines of the character disclosed, the combination with a flatwise reversible knife block support for removably holding, in reversible substantially horizontal disposition, a knife block that mounts endwise paired cossette slicing knives, of means carried by said reversible support and co-operating with complementary means of said knife block for centering the latter on its support, and mechanical centering 130

means adapted to span the abutting ends of said knives, when so properly disposed, being radially operable thereof to engage and adjust said knives in an endwise direction 5 relatively to each other, substantially as described.

5. In knife setting machines of the character disclosed, the combination with a knife block support for removably holding, in substantially horizontal disposition, a segmentally shaped knife block that mounts successive sets of endwise paired cossette slicing knives, of a support suitably mounted to be moved in association with said successive sets 10 of knives, a bar carried by said latter support and radially operable relatively to said knives, and a centering shoe carried by said bar and providing a serrated face, having an intermediate gap, adapted to span the abutting 15 ends of said knives in engagement with the latter, to adjust the same in an endwise direction relatively to each other, substantially as described.

6. In knife setting machines of the character disclosed, the combination with a flatwise reversible knife block support for removably holding, in reversible substantially horizontal disposition, a segmentally shaped knife block that mounts successive sets of 20 endwise paired cossette slicing knives, of a support suitably mounted to be moved in association with said successive sets of knives, a bar carried by said latter support and rectilinearly operable radially of said knives, and 25 a centering shoe carried by said bar and providing a serrated face, having an intermediate gap, adapted to span the abutting ends of said knives in engagement with the latter, to adjust the same in an endwise direction 30 relatively to each other, substantially as described.

7. In knife setting machines of the character disclosed, the combination with a vertical support providing a forwardly projecting outer arm and a shorter projection spaced from the latter, of a knife block support extending as a flatwise continuation of said shorter projection, for removably holding a segmentally shaped knife block that 40 mounts successive sets of endwise paired cossette slicing knives, a radius arm pivotally connected to said outer arm to swing transversely of said knife block support, a plunger rod carried by the free end of said radius arm, and a knife centering shoe carried by 45 said plunger rod and providing a suitable engaging face co-operating with the abutting ends of said knives, substantially as described.

60 8. In knife setting machines of the character disclosed, the combination with a vertical support providing a forwardly projecting outer arm and a shorter rigid arm spaced therefrom in substantially the same plane, of

a knife block support extending as a flatwise reversible continuation of said shorter arm, for removably holding a segmentally shaped knife block that mounts successive sets of endwise paired cossette slicing knives, a radius arm pivotally connected to said outer arm to swing transversely of said knife block support, a plunger rod carried by the free end of said radius arm and operable rectilinearly thereof, and a centering shoe carried by said plunger rod and providing a suitable engaging face co-operating with the abutting ends of said knives, substantially as described.

9. In knife setting machines of the character disclosed, the combination with a vertical support providing a forwardly projecting outer arm and a shorter arm spaced therefrom in substantially the same plane, of a knife block support extending flatwise as a continuation of said shorter arm, for 80 removably holding a segmentally shaped knife block that mounts successive sets of endwise paired cossette slicing knives, a radius arm pivotally connected to said outer arm to swing transversely of said knife block 90 support, latching means cooperating between said outer arm and said radius arm, a plunger rod carried by the free end of said radius arm, and a centering shoe carried by said plunger rod and providing a 95 suitable engaging face co-operating with the abutting ends of said knives, substantially as described.

10. In knife setting machines of the character disclosed, the combination with a vertical support providing a forwardly projecting outer arm and a shorter arm spaced therefrom in substantially the same plane, of a knife block support extending as a flatwise continuation of said shorter arm, for 100 removably holding a segmentally shaped knife block that mounts successive sets of endwise paired cossette slicing knives, a radius arm pivotally connected to said outer arm to swing transversely of said knife 105 block support, a counterbalancing attachment for the upper end of said radius arm, a plunger rod carried by the free end of said radius arm, and a centering shoe carried by said plunger rod and providing a suitable 110 engaging face co-operating with the abutting ends of said knives, substantially as described.

11. In knife setting machines of the character disclosed, the combination with a vertical support providing a forwardly projecting outer arm and a shorter projection spaced from the latter, of a knife block support extending as a flatwise continuation of said shorter projection, for removably holding a segmentally shaped knife block that mounts successive sets of endwise paired cossette slicing knives, setting means co-oper- 115 120 125

ating with complementary means of said knife block for centering the latter on its support, a radius arm pivotally connected to said outer arm to swing transversely of said 5 knife block support, a plunger rod carried by the free end of said radius arm, and a centering shoe carried by said plunger rod and providing a suitable serrated engaging face co-operating with the abutting ends of 10 said knives, substantially as described.

12. In knife setting machines of the character disclosed, the combination with a vertical support providing a forwardly projecting outer arm and a shorter projection 15 spaced from the latter, of a knife block support extending as a bifurcated continuation of said shorter projection and providing internal longitudinal ledges, to slidably receive and hold a segmentally shaped knife 20 block that mounts successive sets of endwise paired cossette slicing knives, a radius arm pivotally connected to said outer arm to swing transversely of said knife block support, and a reciprocating knife centering 25 shoe operable longitudinally of said radius arm and providing a suitable engaging face

co-operating with the abutting ends of said knives, substantially as described.

13. In a knife setting machine of the character disclosed, the combination with a vertical support providing a lateral cylindrical stub, of a knife block support embodying a base bar having a rear central hub sleeve, revolvably encompassing said stub, and forward elongated bifurcate arms, which are 30 substantially spaced apart and provide internal longitudinal seating ledges, to removably support a segmentally shaped knife block that mounts successive sets of endwise paired cossette slicing knives, an axis pin 35 element revolvably holding said base bar up against said stub end, means for locking said hub sleeve to said stub, a pivotal arm supported from said vertical support to swing transversely of said knife block support, and a knife centering shoe reciprocatingly mounted towards the free end of said pivotal arm and providing a suitable engaging face co-operating with the abutting ends of 40 said knives, substantially as described. 45

In testimony whereof, I affix my signature.
NELSON A. LOCKWOOD.
